US0D1096733S

(12) **United States Design Patent** (10) **Patent No.:** **US D1,096,733 S**
(45) **Date of Patent:** **** Oct. 7, 2025**

(54) **NETWORK STORAGE DEVICE**

(71) Applicant: **Anhui Sharetronic Data Technology Co., Ltd**, Hefei (CN)

(72) Inventors: **Sihua Geng**, Hefei (CN); **Zhou Yi**, Hefei (CN); **Jianfei Liu**, Hefei (CN)

(73) Assignee: **Anhui Sharetronic Data Technology Co., Ltd**, Hefei (CN)

(**) Term: **15 Years**

(21) Appl. No.: **29/943,206**

(22) Filed: **May 20, 2024**

(30) **Foreign Application Priority Data**

May 11, 2024 (CN) 202430276995.9

(51) **LOC (15) Cl.** **14-02**

(52) **U.S. Cl.**

CLAIM

The ornamental design for a network storage device, as shown and described.

DESCRIPTION

FIG. 1 is a perspective view of a network storage device; FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the network storage device that form no part of the claimed design.

1 Claim, 8 Drawing Sheets
